UNITED STATES PATENT OFFICE.

CLARENCE A. HARDY, OF NAPOLEON, OHIO.

TYPE LIFTER.

Application filed November 5, 1928. Serial No. 317,472.

The present invention relates to lifters for blocks of type from the type bed and is adapted particularly for the removal of a block of type from a newspaper set up or 5 the like.

It frequently happens that in the setting up of newspaper type or the like, that an advertisement is frequently included and set up with the type and which oftentimes 10 must be removed from the set up without interference with the remainder of the type.

It is accordingly the purpose of the present invention to provide a type lifter embodying a plurality of adjustable clamp- 15 ing members for engaging the opposite sides of the block of type desired to be removed from the set up for removing the same as a unit from the bed of the type.

A still further object is to provide an apparatus of this character of a simple and 20 practical construction, which is efficient and reliable in performance, relatively inexpensive to manufacture and otherwise well adapted for the purposes for which the same 25 is intended.

Other objects and advantages reside in the special construction, combination and arrangement of the various elements forming the invention as more fully hereinafter de- 30 scribed and claimed, reference being had to the accompanying drawings forming part hereof, wherein like numerals refer to like parts throughout, and in which:

Figure 1 is a top plan view showing the 35 device in lifting position with respect to a block of type,

Figure 2 is a vertical sectional view thereof,

Figure 3 is an end elevational view,

Figure 4 is a plan view of the threaded face of the scroll plate,

Figure 5 is a side elevational view showing the gripping face of one of the clamping members,

Figure 6 is a perspective view of the supporting bracket for the clamping member,

Figure 7 is a similar view of the guide block for the adjustable arm,

Figure 8 is a similar view of the leaf 50 spring utilized for retaining the adjustable arm in position upon the clamping bracket and

Figure 9 is a similar view of the friction gripping face of the clamp.

Referring now to the drawings in detail, 55 for the purpose of illustration I have disclosed my invention as comprising an annular block 5 having one face formed with a pair of grooves 6 disposed at right angles to each other and intersecting at the center 60 of the block.

As clearly illustrated in Figure 7 of the drawings, the grooves 6 extend through the greater portion of the height of the block. A plurality of arms 7 are arranged with one 65 end slidably disposed in the respective ends of each of the grooves 6, said arms having their upper edges adjacent the block formed with teeth 8 adapted for engagement by the spirally formed thread 9 formed on the un- 70 der side of a scroll plate 10.

The scroll plate is mounted upon the block 5 in superposed relation and is secured in engagement with the teeth 8 of the arm for rotary movement independent of the block 75 by means of a cap 11 provided with an annular flange 12 seated upon a shoulder 13 formed at the inner periphery of said scroll plate.

The cap 11 is secured to the block 5 by 80 bolts or screws 14 inserted through the cap with their lower ends inserted in threaded opening 15 formed in the upper surface of the block.

The scroll plate 10 is thus secured upon 85 the block for rotary movement and upon such movement it will be apparent that the arms 7 will be slidably adjusted inwardly or outwardly of the block depending upon the direction of rotation of said scroll plate. 90 The outer surface of the scroll plate is milled as shown at 16 to facilitate the gripping thereof by the hand of the operator.

A clamping bracket 17 is carried on each of the arms 7, said bracket being of a sub- 95 substantially U-shaped formation with its parallel ends 18 extending upwardly and provided with vertically slotted openings 19 through which the arm 7 is inserted.

The lower edge of one of the slotted openings 19 is beveled as shown at 20 for engaging teeth 21 formed on the lower edge of the arm 7. A leaf spring 22 is inserted between the upper edge of said slotted opening and

the upper edge of the arm 7 whereby to yieldably retain the teeth 21 in engagement with the flanged edge 20 of the slotted opening.

5 The leaf spring 22 is notched at its opposite edges, as shown at 23 within which to receive the opposite side edges of the slotted opening and prevent accidental displacement of the spring from its position upon the upper edge of the arm.

10 The inner end of the bracket 17 is formed with a pair of openings 24 through which bolts or rivets 25 are inserted for attaching a clamping plate 27 to the bracket, said 15 clamping plate extending below the bracket and has the lower portion of its inner face milled as shown at 27 to insure a friction gripping engagement of the plate with the sides of the block of type shown by the dotted lines at 28. By providing each of the 20 arms 7 with a clamping bracket of the character specified it will be apparent that the clamping plate carried by the bracket may be arranged in opposed clamping position 25 at the four sides of the block of type and by moving the arms inwardly through the proper manipulation of the scroll plate 10, the clamping plate will tightly engage the block of type and permit removal thereof 30 from the set up as a unit. The engagement of the bracket by the teeth 21 of the respective arms permits of an approximate adjustment of the clamping brackets at the sides of the block of type and through the manipulation of the scroll plate 10 the clamping plates will then be tightly clamped in position thereupon.

It is obvious that my invention is susceptible to various changes and modifications in 40 construction without departing from the spirit of the invention or the scope of the appended claims, and I accordingly claim all such forms of the device to which I am entitled.

45 Having thus described my invention, what I claim as new is:

1. A type lifter of the class described comprising a block having grooves formed radially thereof and intersecting at the center of the block, an arm slidably mounted 50 in each of said grooves, teeth formed on the upper and lower edges of said arm, a scroll plate mounted upon said block with its threaded face disposed downwardly in engagement with the teeth of the upper edge of said arm, a retaining cap for said scroll plate securing the same for rotation upon the block and a clamping member carried by each of said arms.

60 2. A type lifter of the class described comprising a block having grooves formed radially thereof and intersecting at the center of the block, an arm slidably mounted in each of said grooves, teeth formed on the 65 upper and lower edges of said arm, a scroll

plate mounted upon said block with its threaded face disposed downwardly in engagement with the teeth of the upper edge of said arm, a retaining cap for said scroll plate securing the same for rotation upon 70 the block and a clamping member carried by each of said arms and engageable with the teeth at the tinder edge thereof for longitudinal adjustment.

3. A type lifter of the class described comprising 75 a block having grooves formed radially thereof and intersecting at the center of the block, an arm slidably mounted in each of said grooves, teeth formed on the upper and lower edges of said arm, a scroll plate mounted upon said block with its threaded face disposed downwardly in engagement with the teeth of the upper edge of said arm, a retaining cap for said scroll plate securing the same for rotation upon 80 the block, a clamping member carried by each of said arms adapted for engagement with the teeth at the lower edge thereof for securing said member in longitudinally adjusted position and spring means yieldably retaining the clamping member in engagement with said teeth.

4. A type lifter of the class described comprising a block having grooves formed 95 radially thereof and intersecting at the center of the block, an arm slidably mounted in each of said grooves, teeth formed on the upper and lower edges of said arm, a scroll plate mounted upon said block with its threaded face disposed downwardly in engagement with the teeth of the upper edge of said arm, a retaining cap for said scroll plate securing the same for rotation upon 100 the block and a clamping member carried by each of said arms adapted for engagement with the teeth at the lower edge thereof for securing said member in longitudinally adjusted position, spring means yieldably retaining the clamping member in engagement 105 with said teeth and a clamping plate carried by each of said clamping members and arranged in opposed relation with respect to each other with their opposed faces milled to provide a friction gripping surface for 110 said plate.

5. A type lifter of the class described comprising an annular block having radially extending grooves formed in one face thereof and intersecting at the center of the block, a plurality of arms having one end slidably mounted in said groove, teeth formed on the upper and lower edges of said arms, a scroll plate mounted upon said block having its threaded face disposed downwardly in engagement with the teeth at the upper edge of the arm, a retaining cap for the scroll plate fixedly secured to the block and arranged to secure the scroll plate for rotary movement, a clamping bracket of a substantially U-shaped formation having its oppo- 115 120 125 130

site ends extended upwardly and provided with vertically slotted openings for receiving the arm, the lower edge of one of said openings being beveled and adapted for engagement with the teeth of the lower edge of the lower arm, a leaf spring carried by the bracket and engageable with the upper edge

of the arm for yieldably retaining the teeth of the arm in engagement with the bracket and a clamping plate secured to the inner 10 edge of each of said brackets.

In testimony whereof I affix my signature.

CLARENCE A. HARDY.
